CLAIM

The ornamental design for a surface cleaning device shaft, as shown and described.

DESCRIPTION

FIG. 1 is a perspective view of a surface cleaning device shaft showing our new design;

FIG. 2 is a front view of the surface cleaning device shaft of FIG. 1;

FIG. 3 is a rear view of the surface cleaning device shaft of FIG. 1;

FIG. 4 is a left side view of the surface cleaning device shaft of FIG. 1;

FIG. 5 is a right side view of the surface cleaning device shaft of FIG. 1;

FIG. 6 is a top view of the surface cleaning device shaft of FIG. 1;

FIG. 7 is a bottom view of the surface cleaning device shaft of FIG. 1; and,

FIG. 8 is an exploded-perspective view of the surface cleaning device shaft showing our new design.

The broken lines in the drawings show portions of the surface cleaning device shaft that form no part of the claimed design.

1 Claim, 8 Drawing Sheets
